UNITED STATES PATENT OFFICE.

HARRY FELDBUSH AND HERMAN MILLER, OF CINCINNATI, OHIO, ASSIGNEES TO WORTHINGTON PUMP AND MACHINERY CORPORATION, OF NEW YORK, N. Y., A CORPORATION OF VIRGINIA.

VALVE.

Application filed July 5, 1922. Serial No. 572,861.

To all whom it may concern:

Be it known that we, HARRY FELDBUSH and HERMAN MILLER, citizens of the United States, residing at Cincinnati, county of 5 Hamilton and State of Ohio, have invented certain new and useful Improvements in Automatic Plate Valves, fully described and represented in the following specification and the accompanying drawings, forming a 10 part of the same.

This invention relates to automatic plate valves of the general class that function by bending substantially uniformly throughout their length, one form of such valve being 15 shown in United States Letters Patent No. 13,991, reissued October 12, 1915; No. 1,341,145, dated May 25, 1920, and No. 1,413,059, dated April 18, 1922, in which the valve functions by bending, the special 20 object of the present invention being to provide an improved valve of this general type. The improved valve is of general application, but will be found of particular value in low pressure work, or in connection with 25 long pressure lines where, due to the surge of the moving medium, the valve plates or strips are frequently thrown against the valve guard with more than usual force, with consequent danger of breakage of the 30 plates.

Briefly stated, the invention contemplates the use of a plurality of valve strips arranged in superposed relation over the valve port or ports. The rear plate thus acts as a 35 buffer to cushion the impact of the valve strip against the guard and damage or breakage is less than with a single strip. The strips, also, may each be made of less thickness than with a single strip, so that 40 the valve will open under a considerably less load than would be required with a single strip, due to the fact that the pressure required to bend such strips varies in accordance with the cube of their thickness, and 45 thus the valve is better adapted for low pressure work. Moreover, as the fibre stresses in the metal strips vary directly in accordance with the square of their thickness, such stresses in the thinner valve strips 50 will be less than with a single plate of standard thickness, and the valve, therefore, has the advantage, for low pressure work, that higher lifts will be obtained before the metal

is stressed as much as with a single plate or strip used under similar conditions. 55

For a full understanding of the invention, a detailed description of a construction embodying the same in a preferred form will now be given, in connection with the accompanying drawings forming a part of this 60 specification, and the novel features of the invention then be pointed out in the claims.

In the drawings—

Figure 1 is a plan view with the valve seat partly broken away to show the construction; 65

Figure 2 is a longitudinal section of the valve, with a portion of the cap broken away to show one of the ports in the cap;

Figure 3 is a section on the line 3—3 of 70 Figs. 1 and 2, and

Figure 4 is a view similar to Fig. 2, with the valve open.

Referring now to the drawings, and particularly to Fig. 1, 10 indicates the valve 75 seat, shown as of circular form and having a plurality of straight ports 1, each of which is controlled by a plurality of valve plates or strips 2, 3 in superposed relation, which, in the construction shown, are arranged to open against the cap or guard 11, the latter being shown as having a series of 80 ports 4 out of line with the valve strips.

In the construction shown, as in Patent No. 1,341,145, the valve strips 2, 3 are held 85 in position and guided without the provision of any recesses or projections on the valve seat 10, the latter thus being formed and finished as a plain surface co-acting with the valves in their closed position, this 90 being the preferred construction. Such strips 2, 3 are held in position against side-wise movement and guided in their opening and closing movements by recesses 5 in the cap, which receive the ends of the superposed strips 2, 3, these recesses having inclined or curved walls on the side toward which the valves open, so as to permit the latter to bend freely in the opening movement, and the side walls, 6, of the recesses, 95 act to hold the strips or plates 2, 3 in position sidewise in line with the ports 1. The strips 2, 3 are advantageously made of slightly different lengths, but of the same width, the top strip 2 being the shorter of the strips. The top strips may be somewhat

- thinner or thicker than the strip next to the valve seat, or of the same thickness. The strips or plates, also, are preferably rounded at their ends, as indicated at 7, to eliminate as far as possible wear which might occur with a sharp angle at such points. By making the top strips 2 slightly shorter than the lower strips, there will be provided the same relative space in the recesses 5, due to the contour of the walls of the guard, with consequent equal freedom of movement of such strips at their ends as is the case with the lower strips.
- The construction of the valve will be clear from the foregoing, and the operation thereof will now be briefly described as follows: In the normal positions of the parts, the valve strips 2, 3 are intended to lie flat on the valve seat 10 above the ports 1, as shown in Figs. 2 and 3, and the opening movement of the strips is limited by the abutment surface of the cap 11.
- It will be understood that the invention may be employed in valve constructions of other form than that shown, and that various changes and modifications may be made in the form and mounting of the valve plates or strips while retaining the invention defined by the claims.
- What is claimed is:
1. The combination with a valve seat having one or more ports, of a plurality of thin elastic valve plates arranged in superposed relation to each other over said port or ports and mounted to bend uniformly in functioning.
  2. The combination with a valve seat having one or more ports, of a plurality of thin elastic valve plates arranged in superposed relation to each other over said port or ports and mounted to bend uniformly in functioning, and an abutment for said plates.
  3. The combination with a valve seat having one or more ports, of a plurality of thin elastic valve plates arranged in superposed relation to each other over said port or ports and mounted to bend uniformly in functioning, means at opposite ends of the valve for holding said valve plates in position and permitting bending thereof, and an abutment for said plates.
  4. The combination with a valve seat having a plain surface, of a plurality of elongated plates of elastic material arranged in superposed relation to each other and normally closing the port or ports and mounted to bend uniformly in functioning, and a cap provided with means at opposite ends of the valve for holding said plates in position and curved to form an abutment for the plates.

In testimony whereof, we have hereunto set our hands.

HARRY FELDBUSH.
HERMAN MILLER.
